DESIGN FOR A DRESS

Albert Kaplan, New York, N. Y.

Application August 2, 1937, Serial No. 70,788

Term of patent 3½ years

To all whom it may concern:

Be it known that I, Albert Kaplan, a citizen of the United States of America, residing in the city of New York, county of New York, and State of New York, have invented a new, original, and ornamental Design for a Dress, of which the following is a specification, reference being had to the accompanying drawing, forming part thereof,

Figure 1 is a front view of a dress showing my new design.

Figure 2 is a rear view thereof.

The characteristic feature of my design resides in the combination on the dress disclosed of the box pleats on the waist section, said pleats being open at their upper ends and merging into the inverted box pleats on the skirt section, as shown.

I claim:

The ornamental design for a dress substantially as shown and described.

ALBERT KAPLAN.
